UNITED STATES PATENT OFFICE.

WARNER L. KELLAR, OF LOVINGTON, ILLINOIS.

CHECK-ROW CORN-PLANTER.

SPECIFICATION forming part of Letters Patent No. 297,697, dated April 29, 1884.

Application filed November 26, 1883. (No model.)

To all whom it may concern:

Be it known that I, WARNER L. KELLAR, a resident of Lovington, in the county of Moultrie and State of Illinois, have invented certain new and useful Improvements in Corn-Planters, of which the following is a specification sufficiently full, clear, and exact to enable any one skilled in the art to which it relates to construct and operate the same.

10 The object of my invention is to produce a corn-planter that will, without the assistance of cord or wire, plant in check-rows sufficiently accurate to permit the corn to be cross-plowed.

15 In constructing my device I use ordinary seed-boxes and dropping mechanism, and the general arrangement of the frame, wheels, seed-boxes, &c., does not materially differ from the usual form of corn-planters.

20 The peculiarities of my device extend only to the mechanism used to impart reciprocating motion to the seed-slides of the planter and to the marker used to indicate by impressions in the ground the position of the hills in the rows.

25 The general features of my device for operating the seed-drop may be briefly described as a series of pinions and shafts that receive continuous rotary motion from a planter-wheel and impart intermittent reciprocating motion 30 to the seed-slide by means of a spring-crank and connecting-rod.

The marking device consists in a pair of bent levers hinged to the planter-frame and operated by the motion of the seed-slides.

35 The specific points of my invention will be hereinafter set forth by reference to the accompanying drawings, in which Figure 1 is a plan of a corn-planter with the tongue and other parts not shown. Fig. 2 is a front elevation of the seed-boxes, showing the construction of the markers with relation thereto. Figs. 3 and 4 show details of the device used to operate the seed-slide of the planter.

40 Planter-wheel s' is provided with a crown gear-wheel (not shown) that meshes with pinion e . The bearing d of pinion e is tubular, and is adapted to move longitudinally on shaft k , with which it rotates. The tubular shaft d terminates in a groove or collar, a' , which 45 forms side bearings for lever a , and permits the longitudinal position of said shaft to be

adjusted by said lever. The motion of wheel s' is conveyed to the seed-slide p' through pinion e , shaft k , pinions l m , shaft n , crank o , and a suitable connecting-rod. The rotary motion of the gearing is converted into reciprocating motion in the seed-slide by means of crank o and the connecting-rod. The motion of the pinions and shafting is continuous rotary, but the motion of the crank is intermittent rotary. 55 The crank is held in position on its shaft by means of a spring, o' , Fig. 4, and this spring permits the shaft to partially rotate when the crank is held rigid. The seed-slide is at all times held rigid during a part of each semi-revolution of the gearing by means of a projection, x , and a rod, i . Rod i is attached to a lever, g , which lever is operated by a double cam, f , (see Fig. 3,) on shaft k . A spring, h , holds rod i in contact with projection x , and the operation of the complete device is as follows: The seed-slide and crank being held rigid by rod i , as shown, the gearing continues to rotate until the pressure of cam f against lever g detaches rod i from the projection, 60 then the accumulated tension of the spring o' , Fig. 4, of the crank causes the seed-slide to operate quickly, thereby making a clean, accurate drop. 65

The above operation is repeated in reversing the motion of the seed-slide, except that rod i engages the opposite side of projection x , and the opposite end of cam f disengages rod i . Before coming in contact with rod i the seed-slide moves sufficiently to raise the 70 ends of the markers clear of the ground. 75

As has been intimated, pinion e may be disconnected from the teeth in wheel s' by means of lever a , and while so disconnected the drop may be hastened or retarded by means of loose 80 mounted lever b and rigid ratchet c .

The marking device consists in levers $p''p''$, which are operated alternately by the motion of the seed-slide p' , one marker coming in contact with the ground at each motion of said 85 slide.

t is the planter-frame.

s s' are the wheels.

r r are the seed-boxes.

p is a projection on seed-slide p' , that facilitates connection with crank o .

q q are also extensions from the seed-slide

that form bearings for the rods that connect said slide with markers p'' .

5 o'' in Fig. 4 shows a series of holes in crank o , by means of which the stroke of the connecting-rod may be made longer or shorter.

The proportion of the pinion e to the gear in wheel s' is such that hills will be dropped at the usual distances apart.

If the planter should get out of check while 10 in operation, the imprints of the markers will at once develop the fact, and by throwing pinion e out of gear and operating the lever b , either backward or forward, as the case demands, the defect may be readily corrected.

15 I am aware that bent arms have heretofore been used in co-operation with the seed-slide to mark the position of the hills in the rows; but in such cases the said arms have raised by the motion of the slide and permitted to 20 fall of their own weight. It is now ascertained that positive downward motion is necessary to

insure satisfactory impressions in the ground.

I claim as new and desire to secure by Letters Patent—

1. The combination, in a corn-planter, of a 25 spring-crank adapted to convert continuous rotary motion from the planter-wheel into reciprocating motion in the seed-slide, and a catch adapted to hold the seed-slide rigid during a partial revolution of said crank, and to 30 release the same by motion from the planter-wheel at the proper time for operating the drop, as set forth.

2. The combination, in a check-row corn-planter, of wheel s' , gearing $e d k l m$, spring-crank o , and seed-slide p' , as and for the purpose set forth.

WARNER L. KELLAR.
